UNITED STATES PATENT OFFICE.

WILLIAM T. BARRATT, OF BENNINGTON, VERMONT, ASSIGNOR TO CHARLES S. KEHOE,
 ANNIE COOPER, AND ALEXANDER J. COOPER EXECUTORS OF CHARLES COOPER,
 DECEASED.

FEED MECHANISM FOR CIRCULAR-KNITTING MACHINES.

Application filed October 6, 1925. Serial No. 60,760.

This invention relates to improvements in
 5 yarn feed mechanisms for circular knitting
 machines and is particularly an improvement
 upon the yarn feed mechanism dis-
 closed in United States Letters Patent No.
 1,191,648 issued to me on July 18, 1916.

The object of the invention is to provide
 a feed for yarn which can be used in feed-
 ing yarn such as is employed in knitting
 10 bathing suits and the like, in which the yarn
 is of a soft character and has a large num-
 ber of very fine filaments projecting there-
 from.

In the invention illustrated and described
 15 in said Letters Patent the yarn feed mech-
 anism is entirely practicable where the yarn
 is of a comparatively hard and more finished
 character, but where the yarn is soft and
 has fine filaments projecting therefrom,
 20 these filaments are caught by the sinkers of
 the sinker wheel and are carried around be-
 tween the sinkers and the sinker cam at a
 time when the yarn is not supposed to be
 feeding, thus causing a great deal of trouble
 25 and interfering with the perfect work of the
 machine.

In the feed mechanism of said patent the
 30 yarn passes through a tension device as il-
 lustrated in Fig. 11 of said patent, and when
 a strand of yarn is not being fed to the
 needles, it is held stationary by the said ten-
 sion device, but when it is fed to the needles,
 35 it is pulled through the tension device, which
 only holds the yarn by friction, and this is
 sufficient where a hard finished yarn is used
 to hold the same stationary when it is not
 being fed to the machine, but it is not suffi-
 40 cient to hold a yarn in position when it is
 not being fed to the needles, which is of
 a soft character with the projecting fila-
 ments referred to, for in that case the yarn
 will be pulled through the tension device as
 45 hereinbefore set forth, when it is supposed
 not to be fed.

The device of this invention holds the
 50 yarn, which is out of operation, positively
 clamped, so that it cannot be pulled along
 into the sinker wheel, as hereinbefore de-
 scribed, when it is out of operation. This
 clamping device is operated by the device of

this invention to clamp the yarn while it is
 being cut and to free the yarn at the proper
 time to allow it to be fed to the needles by
 the sinkers and thereafter to be fed to the
 needles until it is time to be cut off again. 55

In so far as the yarn guides are concerned
 and the mechanism which operates them, the
 device of this invention is substantially the
 same as the device for the same purpose dis-
 closed in said Letters Patent. It is the de- 60
 vice for clamping and freeing the yarn, in
 combination with the yarn guides and their
 operating mechanisms, which constitutes the
 principal novelty of this invention.

The invention consists in the improved 65
 mechanism and devices for automatically
 controlling the feeding of the yarn to the
 needles, and especially for automatically
 clamping the yarn which is out of operation
 as it is being cut and for automatically free- 70
 ing said yarn to allow it to feed at the
 proper time in the operation of the machine.

The invention further consists in the im-
 proved mechanism for severing the yarn
 and for holding the free end of the yarn 75
 which has been severed adjacent to the cut-
 ters in an inoperative position until the
 proper time comes in the operation of the
 machine for it to be released.

The invention further consists in the com- 80
 bination and arrangement of parts set forth
 in the following specification and particu-
 larly pointed out in the claims thereof.

Referring to the drawings:

Figure 1 is a sectional elevation illustrat- 85
 ing a portion of a circular knitting machine
 embodying two conical needle cylinders with
 my improved yarn feeding mechanism
 shown in connection therewith.

Fig. 2 is a front elevation viewed from the 90
 right of Figure 1, and illustrating a part of
 the yarn feeding portion of the mechanism
 which operates the guides and also operates
 the yarn clamping mechanism.

Fig. 3 is a plan view illustrating the yarn 95
 guides and yarn clamping mechanisms.

Fig. 4 is a detail side elevation viewed in
 the opposite direction to that in which Fig-
 ure 1 is viewed and illustrating a portion 100
 of the yarn clamping device in the position

occupied thereby when the yarn is clamped so that it cannot feed.

Fig. 5 is a side elevation similar to Figure 4, illustrating the clamp in the position occupied thereby when the yarn is free to feed.

Fig. 6 is a side elevation similar to Figs. 4 and 5, showing the clamp in position to allow the yarn to feed and it being held in 10 said position by a different means from that shown in Fig. 5, namely, a stop shaft.

Fig. 7 is a perspective view of the stop shaft for holding the yarn clamps out of clamping position.

15 Fig. 8 is a detail sectional elevation illustrating the mechanism for severing the yarn in its relative location to the needle cylinders.

Fig. 9 is an elevation of a portion of the 20 mechanism for operating the yarn guides and the yarn clamps as viewed in the opposite direction from Fig. 2, that is, from the rear of the feed mechanism looking outwardly from the needle cylinders and with 25 the slide which operates the yarn guide and cutter mechanisms shown in section.

Fig. 10 is a side elevation of a portion of the yarn guide and clamping mechanisms as viewed from the right of Fig. 2.

30 Fig. 11 is a sectional elevation taken on line 11—11, Fig. 3, illustrating the yarn guides and in connection therewith the yarn cutting and holding mechanisms.

35 Fig. 12 is a sectional plan taken on line 12—12, Fig. 11, and in addition to the mechanism shown in Fig. 11, a portion of the sinker wheel is illustrated in connection therewith.

40 Fig. 13 is a detail sectional elevation taken on line 13—13, Fig. 12.

Fig. 14 is a front elevation of one form of sinker.

45 Fig. 15 is a front elevation of another form of sinker.

Like numerals refer to like parts throughout the several views of the drawings.

In the drawings, 22 is the lower needle cylinder which is fast to a running ring 23, rotatably supported upon a bed plate 24. A 50 gear 26 is fastened to the running ring 23 and is driven by a pinion, not shown in the drawings, but operated by the mechanism described in said Letters Patent. An upper needle cylinder 33 is fastened to a gear 34, which in turn is fastened to a running ring 35, said running ring being constructed to rotate in an upper bed plate 36. The upper cylinder is rotated by means of the gear 34, which in turn is rotated by 55 means of a pinion not shown in the drawings. The lower cylinder 22 is provided with a set of spring needles 39, and these are the primary needles. Said needles are adapted to slide in grooves 40 formed in the 60 periphery of the primary cylinder 22. Each

of said needles has attached thereto a jack 41, and said needles and their jacks have a reciprocating motion imparted thereto, in a manner well known to those skilled in the art, by the primary cams 42 fast to brackets 43, which in turn are fastened to the bed plate 24.

The upper or secondary set of needles 44 are mounted to slide in grooves 45 in the periphery of the secondary cylinder 33. 75 These upper needles are provided with jacks 46 which engage cams 47 fast to the brackets 48 and thus a reciprocating motion is imparted to the upper needles in a manner well known to those skilled in this art.

The primary needles are pressed to cast off their old loops by a stationary presser, and the secondary needles are pressed to cast off their loops by a rotary presser, all in a manner well known to those skilled in 85 this art.

The sinkers 50 and 51 are illustrated in detail in Figs. 14 and 15 respectively. These sinkers are mounted upon a sinker wheel 52 which is fastened to and is rotatable with a gear 53, said gear being rotatably mounted upon a stud 54, fast to a bracket 55, which in turn is adjustably fastened to a bracket 56 by means of a set screw 57, the bracket 56 being fastened to the bed plate 24. The gear 53 has a rotary motion imparted thereto by the needles 39 into which the teeth of said gear mesh. The detail construction of this sinker wheel and the general manner of its operation is fully illustrated in United States patent issued to me August 27, 1907, No. 864,354. When the sinker wheel is rotated by the gear 53, a reciprocating motion is imparted to the sinkers 50 and 51 by a sinker cam 58 fast to 105 the stud 54, whereby the same are moved in and out between primary needles 39, in a manner well known to those skilled in the art, and the yarn is thus fed to the primary needles, which take said yarn and 110 feed it to the secondary needles in the usual manner.

In this embodiment of my invention there are two yarn guides 60 and 61, see Figs. 1, 3, 11 and 12. The yarn guide 60 consists of a thin strip of metal fastened by a screw 62 to a hub 63. Said yarn guide is fastened as a whole to a rock shaft 64 adapted to rock in suitable bearings in a bracket 65, which in turn is fastened to the bed plate 24. To the opposite end of the rock shaft 64 is fastened a rocker arm 66, and this rocker arm is connected by a link 67 to an arm 68 fast to a rock shaft 69 journalled in the bracket 65 and having fastened thereto 120 at its opposite end another arm 70 which bears against a cam plate 71. The link 67 is made adjustable longitudinally thereof by means of a right and left hand adjusting nut 67' which engages correspondingly 125 130

screw-threaded ends of two rods, forming as a whole the link 67.

The cam plate 71 is fastened to another cam plate 74 which constitutes a flange 5 forming a portion of a collar 72, which is rotatably mounted upon a stud 73 fast to the bracket 65.

The yarn guide 61 also consists of a flat piece of metal fastened to a hub 84, Fig. 3, 10 by a screw 85, and said yarn guide is fastened to a rock shaft 86, journalled in suitable bearings in the bracket 65, said rock shaft having fastened at its opposite end a rocker arm 87, to which is attached a link 15 88, the lower end of said link, Fig. 2, being pivotally connected to an arm 89 which, in turn, is fastened to a rock shaft 90 journalled to rock in bearings provided in the bracket 65, and to the other end of the shaft 20 90, and adjacent to the primary cylinder 22, is fastened an arm 91, the free end of which is adapted to bear against the cam plate 74.

It will be seen that if a rotary motion is 25 imparted to the yarn guide cams 71 and 74, a rocking motion would be imparted to the arms 70 and 91, to the rock shafts 69 and 90, and to the arms 68 and 89 respectively, thus through the links 67 and 88 a rocking 30 motion will be imparted to the arms 66 and 87 respectively and to their rock shafts 64 and 86, and thus to the respective yarn guides 60 and 61.

A rotary member 92, Figs. 1, 9 and 10, is 35 fastened to the collar 72, and this rotary member has a plurality of arms 93, 93', extending radially therefrom, and hence said arms are fast to the cams 74 and 71. An intermittent rotary motion is imparted to the 40 member 92 and hence to the cams 71 and 74 by means movable with the primary cylinder 22, said means consists preferably of a slide 94, see Fig. 1.

The slide 14 is slidable in ways formed 45 in a bracket 95, which is fastened by a clamp 96 and screw 97 to the gear 26, it being understood that the gear 26, running ring 23, and the primary cylinder 22 are fastened 50 rigidly together and constitute in effect one piece.

The arms 70 and 91 are each held in engagement with the cam plates 71 and 74 respectively by springs 27 and 28 which are fastened at one end to the bracket 65 and at the other end to arms 29 and 30 fastened 55 to collars 31 and 32, which in turn are fastened respectively to the rock shafts 64 and 86.

A yarn 98 runs from a bobbin constituting 60 a yarn supply, not shown in the drawings, through an eye 99 on a stationary yarn guide 100, which consists of two arms 101 and 102 and a cross bar 103, in which the eye 99 is positioned. The arm 102 is fastened 65 by a screw 104 to the bracket 65. From the

eye 99 the yarn 98 extends downwardly through an eye 105 which is positioned in a spring clamp plate 106, the rear end of which is fastened to a rocker arm 107, pivoted at 107' to the bracket 65. The yarn 70 98 runs from the eye 105 through an eye 108 adjacent the rear end of the clamp plate 106 and from the eye 108 the yarn 98 runs through an eye 109 in a right angle bracket 110, which is fastened to the bracket 65. 75 From the eye 109 the yarn 98 runs through an eye 111 and eyes 112 and 113 provided on the yarn guide 60. From the eye 113 the yarn 98 runs to the needles.

A yarn 114 runs through an eye 115 in 80 the yarn guide 100, thence downwardly and through an eye 116 in a spring clamp plate 117, then along underneath the clamp plate 117 and upwardly through an eye 118 therein, thence through an eye 119 in the right angle bracket 110 and through eyes 120, 121 and 122, which are provided in the yarn 85 guide 61. The rear end of the clamp plate 117 is pivoted to the bracket 65 by a rocker 90 arm 123 and screw 123'.

The upper portion of the link 67 has an arm 124 fastened thereto and a rod 125 extends upwardly from the outer end of said arm to engage the underside of the yarn clamp plate 106 during certain times in the 95 operation of the feed device, and a spring 126 is connected at its upper end to the yarn clamp plate 106 and at its lower end to the rod 125. An arm 127 is fastened to the link 100 88 and has a rod 128 fast thereto, with its upper end adapted to engage the yarn clamp plate 117. A spring 129 is connected at its upper end to the yarn clamp plate 117 and at its lower end to the rod 128.

A stop shaft 130, shown in detail in Fig. 105 7, is rotatably mounted in a bracket 131, Fig. 2, and projects beneath the spring clamp plates 106 and 117. Said stop shaft is flattened off at 132 and at 133 and the flattened-off portion 132 is provided with a 110 notch 134 on its rear edge. The flattened-off portion 132 is positioned beneath the spring clamp plate 106. The flattened-off portion 133 extends beneath the spring clamp plate 117, 115 as will be seen in Fig. 2. A rocking motion is imparted to the stop shaft 130 by an arm 135 which is fastened thereto and is connected by a link 136 to an arm 137. The arm 137 is fastened to a rock shaft 138, 120 mounted to rock in the bracket 65. A rocking motion is imparted to the rock shaft 138 by an arm 139 which is fastened to the rock shaft 138 and has a cam-shaped upper edge 141, which is engaged at certain times in the operation of the device by the outer end 125 of the slide 94. The stop shaft 130 constitutes a stop for the clamp plates 106 and 117.

A spring 142, Fig. 2, is fastened at its upper end to the bracket 65 and at its lower 130 end to the arm 137. A stop plate 143,

fastened to the bracket 65, limits the distance to which the arm 137 can be moved upwardly by the spring 142. The arm 137 is held downwardly in the position illustrated in Fig. 2 during certain times in the operation of the device by a stop lever 144, see Figs. 2 and 10. This lever is pivoted at 145 to the bracket 65 and has a vertical arm 146 terminating at its upper end in a hook 147, which at certain times in the operation of the device, hooks over the upper edge of the arm 137 and holds it in the position illustrated in Figs. 2 and 10. The lever 144 also has a horizontal arm 148, to which one end 10 of a spring 149 is attached, the upper end of said spring being attached to the bracket 65. The lever 144 is rocked upon its pivot 145 to disengage the hook 147 from the arm 137 by any one of the arms 93, 93' during 15 the intermittent rotary motion of the rotary member 92, as will be seen by reference to Figs. 9 and 10, that is, as one arm 93' moves downwardly, it will engage the outer end of the horizontal arm 148 of the lever 144 and 20 push it downwardly until the hook 147 is disengaged from the arm 137, allowing it to be moved upwardly by the spring 142.

It will be understood that when one of the yarn guides carries its respective yarn 30 out of operative position relatively to the needles, said yarn is cut off and clamped by its respective spring clamp plate, that is, the yarn 98 will be clamped by the spring clamp plate 106 when the yarn is being cut. It is 35 evident that if it were clamped before it is cut, the yarn would be broken by the continued circumferential movement of the needles with which it is in engagement.

The severing of the yarn is performed by 40 a cutting mechanism illustrated in Figures 8, 11 and 12 and consisting of a stationary cutter blade 151 which is fastened to a vertical stationary shaft 152 which is fastened to a bracket 153, which in turn, is fastened 45 to another bracket 153' which is fastened to the underside of the upper bed plate 36, see Fig. 8. A movable cutter 154 is fastened to a hollow shaft 155 mounted upon the stationary shaft 152.

A rocking motion is imparted to the hollow shaft 155 and the movable cutter 154 by 50 an arm 156 which is fastened to said hollow shaft and is provided with a slot 157, through which one arm 158 of a bell-crank 55 lever 159 projects. The bell-crank lever 159 is pivoted at 160 to the bracket 153 and has a rocking motion imparted thereto by a link 161, the upper end of which is pivotally connected to an arm 162 of said bell-crank 60 lever, and the lower end of which is pivotally connected to the arm 137. Another arm 163 is fastened to the sleeve 155 and has a spring plate 164, constituting a yarn holder, attached thereto. This spring plate, when the 65 parts are in the positions illustrated in Fig.

12, bears against the free end of the yarn 98 and holds it against an inclined face 165 formed on one end of a block 166, which is fastened to a cam plate 167 of the sinker wheel 52.

A spring 168 encircles the shaft 152 between a collar 169 which is fastened to the shaft 152 and the arm 156, thus operating to hold the movable cutter 154 downwardly against the upper face of the stationary cutter 151, with a yielding pressure.

It is evident that when the slide 94 engages the cam-shaped edge 141 of the arm 139 it will impart a rocking movement to the rock shaft 138 and to the rocker arm 137, 70 and pulling the link 161 downwardly, will rock the bell-crank lever 159, and through the arm 158 of said bell-crank lever and the arm 156 on the hollow shaft 155, the cutter blade 154 will be moved to cooperate with 75 the cutter blade 151 and cut the yarn which may be interposed between said blades.

The cutter blade 151 is held in an open position by the spring 142, which tends to move the arm 137, link 161 and arm 162 upwardly.

At the same time that the cutter blade 154 is moved to cut the yarn, the spring holder arm 164 will be moved in the direction to hold the yarn 98 against the inclined 80 end 165 of the block 166. Thus it will be seen that each yarn, as it is cut, will be held at its free end by the holder 164 at one side of the sinkers which are operating to insert the yarn between the needles and will 85 be clamped by its respective clamp plate on the opposite side of said sinkers from the holder 164.

It will be understood that the spring holding arm 164 holds the free end of the yarn 98 against the stationary member 166 to prevent the free end from snapping or flopping around or missing the sinkers when its respective yarn guide is lowered to change the color. If the yarn were left to hang free 100 from the end of its yarn guide, it would make the action somewhat uncertain when the yarn guide is suddenly lowered to feed it into the sinkers, and it has been found that unless the free end of the yarn is held, an 105 occasional press-off will occur and result in bad work and loss of time.

When using certain kinds of yarn, the holding arm 164 would hold the yarn tight enough without the use of the clamping plate 106, or 117, as the case may be, but with wool or worsted yarns, having long strong fibers sticking out, the holding arm 164 would not be sufficient, for the reasons that the sinkers spinning swiftly around 110 would draw the fibers down and pinch them between themselves and the sinker wheel cap and draw the thread out of the holder and wind it around the sinker wheel and clog it 115 up, causing it to throw out and stop the 120

machine. It, therefore, became necessary to add the clamps 106 and 117 to obviate this trouble.

The general operation of the mechanism hereinbefore specifically described is as follows:—Assuming the parts to be in the relative positions illustrated in Figures 1, 2, 3, 4, 8, 9, 10, 11, 12 and 13. At this time the yarn guide 60 is raised out of operation, the 10 yarn 98 has been severed, and its free end is held against the inclined face 165 of the stationary member or block 166 by the spring holding plate 164, and with the cutter 154 in closed position, the yarn 98 is also 15 clamped by the clamping plate 106 against the bracket 65. The stop shaft 130 is in the position shown in Fig. 4 with the flat portion 132 thereof parallel to the clamping plate 106 and spaced apart therefrom. The yarn 20 guide 61 is in lowered operative position with the yarn 114 feeding to the needles and free from the spring holding plate 164, the cutters and the clamping plate 117 which is held up by the rod 128. The flat portion 133 25 of the stop shaft 130 is parallel to the clamp plate 117 and is spaced apart therefrom.

Assuming that the slide 94 now moves in the direction of the arrow *a*, Fig. 9, the different parts will be operated as follows:— 30 The cam plate 71 frees the arm 70 and allows it to be rocked, together with the rock shaft 69, in the direction of the arrow *c*, Fig. 9, thus moving the arm 68, Fig. 2, upwardly, moving the link 67 and arm 66 upwardly, 35 and rocking the shaft 64 to move the yarn guide 60 downwardly into operative position. At the same time, the rod 125 lifts the clamp plate 106 and frees the yarn 98 from the pressure of said clamping plate as shown 40 in Figure 5.

While this operation has been taking place, the arm 93' engages the arm 148 of the lever 144, Figs. 9 and 10, and tips it to enable the hook 147 to release the arm 137, 45 Fig. 2, and allow it together with the arm 139, both of which are fast to the rock shaft 138, to be moved upwardly by the spring 142 until the arm 137 strikes the stop plate 143, Figs. 2 and 10. The upward movement 50 of the arm 137, through the link 161, rocks the arm 135 toward the right, Fig. 8, and opens the cutter blade 154 and releases the yarn 98 from the pressure of the holding arm 164. At the same time, the link 136 rocks 55 the arm 135 and thus rocks the stop shaft 130 to the position illustrated in Fig. 6, with the corner 130' positioned to hold the clamp plates 106 and 117 up and the yarns 98 and 114 free to feed.

The guide arms are now both in the lowered position, the cutter 154 is open, the holding arm 164 is thrown back, and the clamping plates 106 and 117 are raised. Now as the slide 94 continues its movement 60 in the direction of the arrow *a*, Fig. 9, the

throw on the cam plate 74 will engage the arm 91, rock the shaft 90 in a direction opposite to that of the arrow *c*, and lower the arm 89, the link 88, arm 87 and rod 128, Fig. 2. This will rock the shaft 86 and raise the 70 yarn guide 61 to the upper position and at the same time allow the clamping plate 117 to rest against the corner 130' of the stop shaft 130, and the needle corresponding to the needle 39', Fig. 11, will carry the yarn 75 114 between the cutters 151 and 154, ready to be severed.

The slide 94 now engages the cam shaped upper edge portion 141 of the arm 139, Figs. 9 and 10, and pushes it down, together with the arm 137, through the rock shaft 138, to which both of said arms are fastened, until the hook 147 snaps over the arm 137 and holds it and the arm 139 down, as in Figs. 2 and 10. When the arms 137 and 139 are 80 moved downwardly, as just described, the link 161 actuates the bell-crank lever 159, Fig. 8, to move the cutter blade 154 into closed position, and at that time the yarn 85 114 will be severed, and at the same time its free end will be pressed by the spring holding arm 164 against the inclined end 165 of the stationary member or block 166. At the same time the downward movement of the 90 arm 137, through the link 136, Fig. 2, will move the arm 135 downwardly and rock the stop shaft 130 from the position shown in Fig. 6 to the position shown in Fig. 4, thus allowing the clamping plate 117 to be pulled downwardly by the spring 129, Fig. 2, and thereby clamp the yarn 114 to the bracket 65, while at the same time the clamping plate 106 is in elevated position to allow the yarn 98 to feed to the needles.

The slide 94 may be actuated at predetermined times by the mechanism described in said Letters Patent to engage and operate the rotary member 92 and the arm 139 with the resultant operations performed by the mechanism hereinbefore described, or the 100 said slide may be positioned out of the path of the arms 93 and 93' and the arm 139, as may be desired, and thus stripes of predetermined widths and colors may be knitted. When the slide again operates the rotary 110 member 92, as hereinbefore described, the yarn guide 61 will be lowered and the yarn guide 60 will be raised, the other parts operating as hereinbefore described.

I claim:—

1. A feed mechanism for a circular knitting machine having, in combination, a yarn guide adapted to feed yarn to the needles of a knitting machine, mechanism to move said yarn guide into and out of operative position relatively to said needles, and means independent of the yarn guide to intermittently clamp said yarn between the yarn supply and said yarn guide to prevent its being fed through said yarn guide.

120

125

130

2. A feed mechanism for a circular knitting machine having, in combination, a yarn guide adapted to feed yarn to the needles of a knitting machine, mechanism adapted to move said yarn guide into and out of operative position relatively to said needles, and means independent of the yarn guide to clamp said yarn between the yarn supply and said yarn guide when said yarn guide is out of operative position to prevent its being fed therethrough. 70
3. A feed mechanism for a circular knitting machine having, in combination, a yarn guide adapted to feed yarn to the needles of a knitting machine, mechanism adapted to move said yarn guide into and out of operative position relatively to said needles, means to sever said yarn between said needles and yarn guide, and means independent of the 15 yarn guide to clamp said yarn between the yarn supply and said yarn guide when the yarn is being severed. 80
4. A feed mechanism for a circular knitting machine having, in combination, a yarn guide adapted to feed yarn to the needles of a knitting machine, mechanism adapted to move said yarn guide into and out of operative position relatively to said needles, means independent of said yarn guide to clamp 20 said yarn between the yarn supply and said yarn guide when said yarn guide is out of operative position, and means to operate said clamping means to release said yarn when said yarn guide is being moved into 25 operative position. 85
5. A feed mechanism for a circular knitting machine having, in combination, a yarn guide adapted to feed yarn to the needles of a knitting machine, mechanism adapted to move said yarn guide into and out of operative position relatively to said needles, means independent of said yarn guide to clamp said 30 yarn between the yarn supply and said yarn guide to prevent its being fed through said 35 yarn guide, and means to operate said clamping means to release said yarn when said yarn guide is in operative position. 90
6. A feed mechanism for a circular knitting machine having, in combination, a yarn guide adapted to feed yarn to the needles of a knitting machine, mechanism adapted to move said yarn guide into and out of operative position relatively to said needles, a clamp member independent of said yarn 40 guide adapted to clamp said yarn between the yarn supply and said yarn guide to prevent its being fed through said 45 yarn guide, and means operated by said yarn guide moving mechanism to move said clamping member into and out of clamping position. 100
7. A feed mechanism for a circular knitting machine having, in combination, a yarn guide adapted to feed yarn to the needles of a knitting machine, mechanism adapted to move said yarn guide into and out of operative position. 110
- tive position relatively to said needles, a clamping member independent of said yarn guide adapted to clamp said yarn between the yarn supply and said yarn guide to prevent its being fed through said yarn guide, means operated by said yarn guide moving mechanism to move said clamping member into and out of clamping position, a stop, and mechanism to alternately position said stop to prevent the said clamping member 75 from being moved into clamping position and to allow it to be moved into clamping position. 120
8. A feed mechanism for a circular knitting machine having, in combination, a yarn guide adapted to feed yarn to the needles of a knitting machine, mechanism adapted to move said yarn guide into and out of operative position relatively to said needles, a stationary member, a clamping member pivoted thereto and provided with guide eyes to guide a yarn between it and said stationary member, and means to actuate said clamping member to alternately press the 150 yarn against the stationary member and release it from such pressure. 130
9. A feed mechanism for a circular knitting machine having, in combination, a yarn guide adapted to feed yarn to the needles of a knitting machine, mechanism adapted to move said yarn guide into and out of operative position relatively to said needles, a stationary member, a clamping member pivoted thereto and provided with guide eyes to guide a yarn between it and said stationary member, means to actuate said clamping member to alternately press the 135 yarn against the stationary member and release it from such pressure, a stop shaft, and mechanism to alternately rock said stop shaft to prevent 105 said clamping member from being moved into clamping position and to allow it to be moved into clamping position. 115
10. A feed mechanism for a circular knitting machine having, in combination, a yarn guide adapted to feed yarn to the needles of a knitting machine, mechanism adapted to move said yarn guide into and out of operative position relatively to said needles, a stationary member, a clamping member pivoted thereto and provided with guide eyes to guide a yarn between it and said stationary member, means to actuate said clamping member to alternately press the 140 yarn against the stationary member and release it from such pressure, a stop shaft having a portion thereof flattened and positioned beneath said clamping member, and mechanism to alternately rock said stop shaft into position to be engaged by said clamping member and thus 120 prevent it from being moved into clamping position and then into position to allow the clamping member to be moved into clamping position. 130
11. A feed mechanism for a circular knit- 135

ting machine having, in combination, a pair of yarn guides each adapted to feed yarn to the needles of a knitting machine, mechanism to alternately move said yarn guides into and out of operative position relatively to said needles, and means independent of said yarn guides to clamp the yarn of each of said yarn guides respectively between the yarn supply and its respective yarn guide when the latter is out of operative position to prevent the yarn from being fed therethrough.

12. A feed mechanism for a circular knitting machine having, in combination, a pair of yarn guides each adapted to feed yarn to the needles of a knitting machine, mechanism to alternately move said yarn guides into and out of operative position relatively to said needles, means to sever each of said yarns between said needles and its respective yarn guide, and means independent of said yarn guides to clamp the yarn of each of said yarn guides respectively between the yarn supply and its respective yarn guide when the yarn is being severed.

13. A feed mechanism for a circular knitting machine having, in combination, a pair of yarn guides each adapted to feed yarn to the needles of a knitting machine, mechanism to alternately move said yarn guides into and out of operative position relatively to said needles, means independent of said yarn guides to clamp the yarn of each of said yarn guides respectively between its respective yarn supply and its yarn guide when the latter is out of operative position, and means to operate said clamping means to release each of said yarns when its respective yarn guide is being operated to move it into operative position.

14. A feed mechanism for a circular knitting machine having, in combination, a yarn guide adapted to feed yarn to the needles of a knitting machine, mechanism adapted to move said yarn guide into and out of operative position relatively to said needles, a sinker wheel and sinkers, means to clamp said yarn in advance of the point where it is fed to the needles by said sinkers, and means to hold the free end of said yarn beyond said point.

15. A feed mechanism for a circular knitting machine having, in combination, a yarn guide adapted to feed yarn to the needles of a knitting machine, mechanism adapted to move said yarn guide into and out of operative position relatively to said needles, means to sever said yarn between said needles and yarn guide, means to clamp said yarn in advance of the point where it is fed to the needles, and means beyond said point to hold the free end of said yarn after it has been severed.

16. A feed mechanism for a circular knitting machine having, in combination, a yarn

guide adapted to feed yarn to the needles of a knitting machine, mechanism adapted to move said yarn guide into and out of operative position relatively to said needles, a sinker wheel and sinkers adapted to insert 70 yarn between the needles, means to sever the yarn beyond the point where it is inserted between the needles by the sinkers and embodying a stationary cutter blade and a movable cutter blade, and means to 75 hold the free end of the yarn against a stationary member after it has been severed.

17. A feed mechanism for a circular knitting machine having, in combination, a yarn guide adapted to feed yarn to the needles 80 of a knitting machine, mechanism adapted to move said yarn guide into and out of operative position relatively to said needles, a sinker wheel and sinkers adapted to insert 85 yarn between the needles, means to sever the yarn beyond the point where it is inserted between the needles by the sinkers and embodying a stationary cutter blade and a movable cutter blade, means to hold 90 the free end of the yarn against a stationary member after it has been severed, and other means adapted to clamp the yarn when it is being severed and positioned in advance of the point where the sinkers insert 95 the yarn between the needles.

18. A feed mechanism for a circular knitting machine having, in combination, a yarn guide adapted to feed yarn to the needles of a knitting machine, mechanism adapted to move said yarn guide into and out of 100 operative position relatively to said needles, means to sever said yarn between the needles and the yarn guide and comprising a stationary cutter, a movable cutter adapted 105 to co-operate therewith, means to rock said movable cutter toward and away from the stationary cutter, a spring holding arm connected to and operable with said movable cutter, a stationary member against which the free end of the yarn may be held by 110 said holding member when the yarn is being severed by the cutters, and means to clamp the yarn in advance of the point where it is fed to the needles.

19. A feed mechanism for a circular knitting machine having, in combination, a pair of yarn guides, each adapted to feed yarn to the needles of a knitting machine, mechanism to alternately move said yarn guides into and out of operative position relatively 115 to said needles, means to clamp the yarn of each of said yarn guides respectively in advance of its respective yarn guide when it is out of operative position, and other means to simultaneously hold the free end 120 of said yarn beyond its yarn guide.

20. A feed mechanism for a circular knitting machine having, in combination, a pair of yarn guides, each adapted to feed yarn 125 to the needles of a knitting machine, mech-

anism to alternately move said yarn guides into and out of operative position relatively to said needles, means to clamp the yarn of each of said guides respectively in advance of its respective yarn guide when it is out of operative position, other means to simultaneously hold the free end of said yarn beyond its yarn guide, and means to operate said clamping and holding means to release each of said yarns respectively when its yarn guide is being moved into operative position.

21. A feed mechanism for a circular knitting machine having, in combination, a pair of yarn guides, each adapted to feed yarn to the needles of a knitting machine, mechanism to alternately move said yarn guides into and out of operative position relatively to said needles, means to sever each of said 15 yarns when its yarn guide is moved out of operative position, means to clamp the yarn of each of said yarn guides respectively in advance of its respective yarn guide when 20 it is out of operative position, and other

means to simultaneously hold the free end 25 of said yarn beyond its yarn guide.

22. A feed mechanism for a circular knitting machine having, in combination, a pair of yarn guides each adapted to feed yarn to the needles of a knitting machine, mechanism to alternately move said yarn guides into and out of operative position relatively to said needles, a sinker wheel and sinkers adapted to insert yarn between the needles, means to sever each of said yarns, when its yarn guide is out of operation, beyond the point where it is inserted between the needles by the sinkers, means to clamp the yarn of each of said yarn guides respectively in advance of the point where it is inserted between the needles by the sinkers when the yarn guide is out of operative position, and other means to simultaneously hold the free end of said yarn beyond said point. 30 35 40

In testimony whereof I have hereunto set my hand. 45

WILLIAM T. BARRATT.
